SQUEEZE CEMENTING OF WELLS

Albert D. Stoddard, Duncan, Okla., assignor to
Halliburton Oil Well Cementing Company,
Duncan, Okla.

Application September 5, 1939, Serial No. 293,371

8 Claims. (CL 166—12)

This invention relates to apparatus adapted for use in oil wells or the like, and more particularly to packers and means for removably securing the same to the casing in a well while forcing cement into the well under pressure.

In the cementing of oil wells, it is sometimes desirable to perform what is known as a "squeeze" job. By this, it is meant that cement slurry is forced or "squeezed" by pressure into or against a permeable formation or through perforations in casing and liners for the purpose of shutting off water or for reducing gas-oil ratio, or for other purposes.

In "squeeze" cementing, it is customary and usually desirable to fix and seal a tubing or other conduit to the casing above the point where the cement slurry is to be forced under pressure. For this purpose, a cement retainer may be employed. Some cement retainers must be drilled up in order to remove them from the well. In other cases, it has been proposed that a removable packer and slips be employed. An example of this latter type of device for retaining the cement is disclosed in the patent to Halliburton, No. 2,138,157, granted November 29, 1938, for "Removable packer for wells."

In all arrangements heretofore proposed for the purposes outlined above, the arrangement has been such that the packer is secured to the casing and held in fixed relation to the casing until after the cement slurry pumped down through tubing or other conduit has hardened. In accordance with the present invention, it is proposed to remove the tubing and packer and slips, which secure the packer to the casing, as soon as the cement slurry has been "squeezed." It has formerly been supposed that the cement retainer must be so used as to hold the cement slurry in place until it sets. It has been discovered, however, that this is not always the case, and the present apparatus and method has been devised for use in cases where the cement retainer need not be employed to retain the cement slurry in place while it sets. Instead of using a cement retainer to retain the slurry in place, hydraulic pressure of fluid in the hole is employed for this purpose.

Accordingly, it is an object of the present invention to provide a device capable for use in the "squeeze" cementing of oil wells or the like in which a packer and tubing are secured to the casing in a well but in which the securing means is so designed that the tubing and packer may be easily removed when desired.

It is a further object of the invention to de-

vise means for securing tubing and a packer to the casing in a well in which said securing means may be released by the application of a predetermined fluid pressure to the fluid beneath the packer.

It is still another object of the invention to devise a novel method for "squeezing" cement or other sealing fluid in oil wells in which a packer is employed on tubing or other conduit 10 and is secured to the casing of the well but is released automatically from the casing when a predetermined pressure is applied to fluid in the well, or when a predetermined tension is taken in the tubing, or when both fluid pressure and tension in the tubing are exerted on the securing means.

Other objects reside in certain novel features of the arrangement, combination of parts and method as will be more apparent from the following description taken in connection with the accompanying drawing, in which:

Figure 1 is a vertical cross-sectional view of the casing of a well with packing and securing apparatus constructed in accordance with the principles of the present invention located therein, the parts being shown in the position which they occupy after they have been lowered through the casing and are about to be set;

Figure 2 is a vertical cross-sectional view of 30 the apparatus of Figure 1 but illustrating the relative positions of the parts when the apparatus is set and secured to the casing in the well, in which position cement slurry may be forced downwardly through the tubing to a point beneath the packer; and

Figure 3 is a vertical cross-sectional view of the apparatus shown in Figures 1 and 2 but illustrating the relative positions of the parts after the tubing and packer have been released from the casing and are being removed from the well.

Referring to the drawing in detail, it will be seen that the casing of an oil well is there illustrated at 11. Within the casing, apparatus constructed in accordance with the present invention may be located. This may be lowered into the casing on tubing or other conduit means, the lower end of which is shown at 12.

Between the tubing and the packer and securing means which constitute the present invention, a circulating sub is provided. In the form illustrated, this consists of two telescoping members 13 and 14, the inner telescoping member being threaded at its upper end and connected to the tubing 12, and the other telescoping member 14 being threaded at its lower end and con-

nected to the mandrel 15 of the slip actuating means which will presently be described. The threaded connection between the members 14 and 15 is preferably a left hand thread so that these parts may be disconnected if desired in case the packer 15 and the slip assembly become stuck in the well.

A suitable packing gland 16 is provided between the members 13 and 14 to prevent leakage when the parts are in the position shown in the drawing, that is, telescoped together. When the parts are extended longitudinally, ports 17 in the lower end of the inner member 13 move above the packing 16 and permit the flow of fluid outwardly through ports 18 in the outer telescoping member 14. The amount of longitudinal extension of the members 13 and 14 is limited by the shoulder 19 which abuts against a seat 20 in a nut 21 connected to the top of the member 14.

The parts 13 and 14 are normally held locked in the collapsed or telescoped positions shown in the drawing by means of pin and J-slot connections, the pins being connected to the member 14 as illustrated at 22, and the slots being provided as shown at 23 in an enlargement 24 on the inner member 13. The arrangement may be such that upon slight rotation to the right, the pins 22 will be brought into the longitudinally extending portions of the J-slots so that upon lifting of the tubing 12 and the inner member 13 fluid may be circulated downwardly through the tubing and out through the ports 17 and 18 as described above. It will be understood that the operation of the elements 13 and 14 can take place only when the member 14 is held both against rotation and against vertical movement.

If the apparatus of the present invention is operated in one way, the circulating sub just described may not be used at all; but when operated in other ways, the circulating sub is opened. In either case, it is good practice to have a circulating sub in the string of tubing so that it may be used if desired.

The mandrel 15 which is connected to the lower end of the circulating sub, as described above, is provided with suitable means for setting slips 25 in the casing. The particular means for setting the slips and for releasing the back pressure valve in the mandrel 15 is similar to that disclosed and claimed in the patent to R. K. Henderson, No. 2,217,747, granted October 15, 1940, for "Drillable packers." As herein shown, it consists of an inner removable sleeve 26 connected inside of the mandrel 15 by means of a shear pin 27. The sleeve 26 is provided with a number of longitudinally extending grooves 28 which receive the heads of pins 29 and positively control movement of the pins as long as the heads thereof are in the grooves. Thus, if the sleeve 26 is drawn upwardly, the pins 29 are moved inwardly.

The sleeve 26 is also provided with a depending rod 30 which holds the back pressure valve open until the sleeve is moved upwardly. The back pressure valve may consist of a ball 31 resting on a spider 32 which carries a coil spring 33 which tends to move the ball 31 upwardly against a seat 34 provided in the lower end of the mandrel 15. As long as the sleeve 26 is in the position illustrated in Figure 1, fluid can pass either upwardly or downwardly through the mandrel 15, but upon the sleeve 26 being pulled upwardly the valve 31 engages the seat 34 and prevents passage of fluid upwardly through the mandrel 75

while still permitting downward flow therethrough. It is possible to construct and operate apparatus in accordance with the present invention without the use of any back pressure valve at all, but it is preferable to provide the back pressure valve.

To shear the pin 27 and pull the sleeve 26 upwardly at any desired time, a special weight member 35 is connected to the lower end of a measuring line 36 and lowered downward through the tubing 12 and the circulating sub. The weight member 35 is provided with spring pressed latch dogs 37 near its lower end which are adapted to secure the weight member 35 to a ring 38 secured to the sleeve 26 by means of longitudinally extending bars 39. Figure 1 illustrates the position of the weight member 35 just before it engages the ring 38. As soon as the weight member 35 is lowered farther into the well, it will be latched to the sleeve 26, and by taking tension in the measuring line 36, the sleeve 26 can be pulled upwardly. The operator will know by the amount of tension in the line when the weight 35 has been latched to the sleeve 26, and will know when the pin 27 shears because of the sudden decrease in tension in the line. By means of suitable depth measuring apparatus, such as that illustrated and described in the patent to Halliburton, No. 1,692,037, granted November 20, 1928, for "Well sounding device," the operator will know exactly where the assembly is located at the time when the inner sleeve 26 is moved upwardly. Upon the sleeve 26 being pulled upwardly, the slips 25 are released and moved outwardly to engage the casing 11. This movement is accomplished under the influence of a coil spring 40 mounted within a housing member 41 screw threaded onto an enlargement 42 on the mandrel 15. The slips are guided and held in position by means of wedge members 43 mounted on the wedge body 44, which is formed on the lower portion of the enlargement 42 on the mandrel 15. It will be noted that the wedge body 44 is tapered downwardly whereas the wedge members 43 are tapered upwardly. In accordance with the usual practice, the slips 25 are dovetailed or splined to the wedge members 43. In turn, the wedge members 43 may be dovetailed or splined to the wedge body 44.

Shearable means is provided between the wedge members 43 and the wedge body 44. This may consist of a split ring or any other shearable means, but in the form shown pins 45 are provided between these members. The lower end of the wedge members 43 may be provided with shoulders 46 for preventing the slips from moving downwardly too far thereon, as will be explained later in connection with Figure 3 of the drawing.

Beneath the slip actuating means, the mandrel 15 connects to the valve housing 47 which carries a tubular member 48 which, in turn, carries a packer 49. The packer 49 may be of a type in common use in the oil fields. It is called a "swab rubber" and consists essentially of a flexible cup of rubber, fabric or the like. When used in the present invention, it is mounted inverted upon the tubular member 48, being clamped in position by a collar 50 shaped to conform with the outer surface of the packer 49 and an inner ring 51. In addition to these members, spring fingers 52 may be employed to hold the swab rubber 49 in place and prevent it turning inside out. In the arrangement illustrated, the packer will prevent the flow of fluid upwardly in the cas-

ing 11 but permit fluid to flow downwardly on the outside thereof. It will be noted that with the particular packer shown no operation is required to effect a seal between the tubing and the casing. However, if other types of packers are used they may be set when the slips are set, as will be obvious to those skilled in the art.

The operation of the apparatus shown in performing a "squeeze" cementing job is as follows:

With the parts in the position shown in Figure 1, the tubing, packer, slips and operating assembly are lowered into the well. When the desired depth has been reached and it is desired to secure the packer and tubing against upward movement with respect to the casing, the measuring line 36 and weight 35 are lowered into the well and the sleeve 26 pulled upwardly, as described above, to release the slips 25. The tubing may then be lifted slightly to cause the wedge members 43 to force the slips 25 to bite into the casing to some extent. After the measuring line, the weight 35 and the sleeve 26 are removed from the well, the apparatus is ready to perform the "squeezing" operation. Before "squeezing" cement into the formation, the formation is first "broken down." This is usually performed by pumping water down through the tubing to a point beneath the packer and building up pressure on the pumps until it is determined that the water is flowing into the formation. When this occurs, cement may be pumped down through the tubing. If it is desired that the water beneath the cement slurry in the tubing shall not be forced back into the formation, the circulating sub described above may then be opened until the cement slurry is circulated down to some point not far above the circulating sub. However, in some cases, there is no objection to forcing the water into the formation ahead of the cement, and in that case the circulating sub would not be opened.

In Figure 2, the parts are shown in the position which they occupy when cement slurry is being forced downwardly through the tubing without the circulating sub being opened. It is common experience in "squeeze" cementing to have the pressure gradually build up as the cement is forced into the formation. The pressures differ in different formations and in different fields, but in most cases the pressure gradually increases until no more cement can be forced into the formation. The shear pins 45 which connect the wedge members 43 to the wedge body 44 are so designed as to take this pressure and a certain additional pressure necessary to effect a factor of safety. However, after as much cement has been forced into the formation as is desired, the pump pressure may be increased until the pins 45 shear. The pins 45 may be sheared, however, merely by pulling upwardly on the tubing 12 or by taking tension in the tubing at the same time that the pump pressure is increased. It is, of course, within the purview of the present invention to provide a rotary jar in the tubing 12 at some point above the circulating sub as an aid in shearing the pins 45 when desired.

When the pins 45 shear, the tubing, packer and slips are entirely disconnected from the casing inasmuch as the wedge body 44 is then free to move upwardly relative to the wedge members 43; and as it does so the slips 25 are drawn inwardly radially due to the spline connections between them and the wedge members 43 and the wedge body 44. The parts are then in the position shown in Figure 3 of the drawing and are ready to be removed from the well. It is desirable in

accordance with the present invention to move the tubing, slips and packer upwardly at least some distance in the well immediately after the cement has been "squeezed" and before it has had a chance to harden. The mud or other fluid which followed the cement into the well and which was used to exert pressure on the cement in "squeezing" it may flow downwardly through the tubing and the back pressure valve 31 as the tubing is moved upwardly. Also, mud outside of the tubing but within the casing may flow downwardly past the packer 49 as the assembly is moved upwardly. This mud pressure may be sufficient to hold the cement slurry which has been "squeezed" into the formation in place until it hardens and prevent it from flowing back into the well. However, if additional pressure is necessary or desirable, the tubing 12 may be run into the well through a blowout preventer or other packing means at the surface. Mud or other fluid can then be forced downwardly under pressure through the tubing while the tubing is being removed from the well and the mud pressure on the formation into which the cement has been "squeezed" thus maintained higher than that which prevails inside the tubing 12 while it is being disjointed at the surface, this excess pressure being held upon the formation by the back pressure valve. In other words, the tubing and packer assembly may be pumped out of the well.

If a circulating sub is employed as illustrated in the drawing, it is possible to circulate cement slurry out of the tubing if it is found that there is more cement in the tubing than can be "squeezed" into the formation. The circulating sub is such that it may be opened for any desired length of time and then again closed and held in locked position by the pin and J-slot arrangement.

While only one embodiment of the invention has been shown and described herein, it is obvious that various changes may be made both in the structure and method without departing from the spirit of the invention or the scope of the annexed claims.

I claim:

1. Apparatus adapted for use in forcing sealing fluid under pressure into an oil well, including a conduit, a packer mounted on the conduit, slips also mounted on the conduit, and mechanism for operating said slips to cause the same to secure the conduit and packer to casing in the well, said mechanism including wedge means for actuating the slips and means connecting said wedge means to said conduit, said connecting means being adapted to shear upon a predetermined shear stress being exerted thereon and means mounted on the conduit and engaging said wedge means and adapted to draw the wedge means inwardly to entirely disconnect said packer and conduit from the casing when said connecting means is sheared.

2. Apparatus adapted for use in forcing fluid under pressure into an oil well, including a conduit, a packer mounted on the conduit and mechanism for connecting the conduit and packer to casing in the well, said mechanism including slip means for gripping the casing and an actuating device for operating said slip means, said actuating device including a wedge member connected to said packer and operable to release said conduit and packer upon the exertion of a predetermined upward pressure upon said packer.

3. Apparatus adapted for use in forcing fluid under pressure into an oil well including a conduit and an arrangement for securing and seal-

ing the lower end of said conduit to casing in the well, said arrangement including a packer mounted on the conduit, casing gripping means mounted on the conduit adjacent said packer, means for setting the gripping means and means operable in response to fluid pressure conditions in the well beneath said packer to release said gripping means.

4. Apparatus adapted for use in forcing sealing fluid under pressure into an oil well including a conduit adapted to be lowered down through casing in the well, a swab rubber mounted inverted upon the lower end of said conduit, means for securing the lower end of said conduit to the casing whereby the swab rubber may be held against movement while fluid is forced downwardly through the conduit, said means including slips and mechanism operable in response to variations to fluid pressure above and beneath said swab rubber for releasing said slip, the arrangement being such that said securing means and said swab rubber may be removed from the well.

5. The method of sealing a formation beneath casing in a well which consists of lowering into the well a conduit, securing and sealing the lower end of the conduit to the casing in the well at a point above the formation to be sealed, placing sealing fluid in the conduit, forcing the sealing fluid down through the conduit by placing in the conduit a following fluid, increasing the pressure on the following fluid to squeeze some or all of the sealing fluid into the formation, disconnecting the conduit from the casing and moving the conduit upwardly while holding the sealing fluid in place in the formation by exerting pressure on the following fluid in the well.

6. Apparatus adapted for use in forcing fluid under pressure into an oil well including a con-

duit and an arrangement for securing and sealing the lower end of said conduit to casing in the well, said arrangement including casing gripping means, a packer, means for actuating said casing gripping means and means for releasably maintaining said casing gripping means in casing gripping position releasably by predetermined fluid pressure beneath said packer in excess of the fluid pressure on the outside of 10 said conduit above said packer.

7. Apparatus adapted for use in squeeze cementing wells, comprising, in combination, a conduit adapted to be run into a well, a circulating sub incorporated in said conduit, a packer mounted on the conduit above the discharge end thereof and below the circulating sub and means for securing said conduit, and said packer to the casing to hold the same against movement while the cementing operations are carried on, said securing means being releasable hydraulically in response to a pressure difference above and below 20 said packer, whereby the entire assembly can be removed from the well after the cementing operations are completed.

8. Apparatus adapted for use in squeeze cementing wells, comprising, in combination, a conduit adapted to be run into a well, a circulating sub incorporated in said conduit, an inverted swab cup mounted on the conduit above the discharge end thereof and below said circulating sub and means for securing said conduit and said swab cup to the casing, to hold the same against movement while the cementing operations are carried on, said securing means being releasable hydraulically, whereby the entire combination can be removed from the well after the cementing operations are completed.

ALBERT D. STODDARD.
